UNITED STATES PATENT OFFICE

148,541

DESIGN FOR A VEHICLE BODY

James H. Holan, Jr., Rocky River, and Herman J. Troche, Cleveland Heights, Ohio, assignors to The American Coach & Body Company, Cleveland, Ohio, a corporation of Ohio

Application July 31, 1946, Serial No. 132,155

Term of patent 14 years

(Cl. D14—3)

To all whom it may concern:

Be it known that we, James H. Holan, Jr., and Herman J. Troche, citizens of the United States, residing at Rocky River, county of Cuyahoga, and State of Ohio, and of Cleveland Heights, county of Cuyahoga, and State of Ohio, respectively, have invented a new, original, and ornamental Design for a Vehicle Body, of which the following is a specification, reference being had to the accompanying drawings, forming a part thereof.

In the drawings, Fig. 1 is a perspective view of a vehicle body showing our new design; Fig. 2 is a top plan view of the body; Fig. 3 is a side elevation showing the left-hand side of the body; Fig. 4 is a side elevation showing the right-hand side of the body; Fig. 5 is an end elevation showing the rear-end of the body, and Fig. 6 is an end elevation showing the front of the body.

The dotted line showing in Fig. 1 of the drawing is for illustrative purposes only.

We claim:

The ornamental design for a vehicle body, as shown and described.

JAMES H. HOLAN, JR.
HERMAN J. TROCHE.
